Inventor:

Edwin A. Wood

United States Patent Office.

EDWIN A. WOOD, OF UTICA, NEW YORK.

Design No. 3,868, dated February 22, 1870.

DESIGN FOR A PRESSURE-GAUGE CASE.

The Schedule referred to in these Letters Patent and making part of the same.

To all whom it may concern:

I, EDWIN A. WOOD, of the city of Utica, in the county of Oneida, and State of New York, have invented and produced a new and original Design for a Pressure-Gauge Case, of which the following is a specification.

The nature of my design is fully represented in the accompanying drawing, to which reference is hereby made.

My gauge-case represents a fluted column, with a

base and capital. A dial is supported upon the side of the column.

Claim.

I claim as my invention—

The design for a pressure-gauge case, as shown.
EDWIN A. WOOD.
